UNITED STATES PATENT OFFICE.

JEROME R. GEORGE, OF WORCESTER, MASSACHUSETTS, ASSIGNOR TO
MORGAN CONSTRUCTION COMPANY, OF WORCESTER, MASSACHU-
SETTS, A CORPORATION OF MASSACHUSETTS.

METHOD OF REDUCING RODS OR BARS.

SPECIFICATION forming part of Letters Patent No. 729,570, dated June 2, 1903.

Original application filed March 10, 1902, Serial No. 97,543. Divided and this application filed July 8, 1902. Serial No. 114,774. (No model.)

To all whom it may concern:

Be it known that I, JEROME R. GEORGE, a citizen of the United States, and a resident of Worcester, in the county of Worcester and 5 Commonwealth of Massachusetts, have invented a new and useful Improvement in Methods of Reducing Rods or Bars, of which the following is a specification, accompanied by drawings forming a part of the same, constituting an application which is a division of my pending application, Serial No. 97,543, for rolling-mills, filed March 10, 1902.

In the accompanying drawings, Figure 1 represents a plan view of a rolling-mill embodying my invention. Fig. 2 is a front elevation of the same, with the conveyer shown in sectional view on line 2 2; Fig. 1. Fig. 3 is a sectional view of the conveyer on line 3 3, Fig. 1; and Fig. 4 is a sectional view of the 20 conveyer on line 4 4, Fig. 1.

Similar reference letters and figures refer to similar parts in the different views.

My present invention has for its object to provide an improved method of effecting the 25 consecutive reduction of a rod or bar by an automatic and continuous movement of the rod or bar through the reducing-passes of a two-high mill; and my invention consists, broadly, in the method of disposing of the rod 30 or bar between the consecutive passes of the rolls, whereby it is conducted or transferred from one of the passes of the rolls around one of the roll-housings to the next consecutive pass.

Referring to the accompanying drawings, A A' denote the housings of a two-high rolling-mill containing upper and lower rolls B B', provided with a series of circumferential grooves or reducing-passes 1, 2, and 3, although their number may be increased or diminished. The grooves 1, 2, and 3 gradually decrease in size in the order named, so that a rod or bar consecutively passed through the grooves from 1 to 3 will be reduced in size and 45 correspondingly increased in length. Extending around one of the roll-housings A are curved channels or tracks, according to the number of passes in the rolls, for conducting or transferring the rod as it leaves the rolls 50 into the next consecutive pass, said channels

or tracks forming the repeaters C and D. The repeater C is provided with a mouth C' in position to receive the rod as it leaves the groove or pass 1 in the rolls, and as the rod is pushed into the mouth C' it is crowded against the 55 corner C² of the mouth C' and against the side wall C³, thereby bending the rod and imparting a curvature approximating the curved repeater C, which extends around the roll-housing A to the next succeeding groove or 60 pass 2 in the rolls. The repeater D is similar to the repeater C and extends around the housing A with its ends in position to receive the rod from the groove or pass 2 of the rolls and deliver it to the next consecutive 65 groove or pass 3 in the rolls. The repeater D, like repeater C, has a mouth D', arranged to receive the rod as it leaves the groove or pass 2, and it successively bends the rod, giving it a curvature approximating the path 70 around the housing A, with the opposite end of the repeater in position to deliver the rod to the next consecutive groove or pass 3. This being the last pass, in the present instance the rod is conducted through the 75 straight channel or run-out F. The bottom F' of the run-out F is slightly inclined from its mouth F², as shown in Fig. 4, for the purpose of raising the advancing end of the rod as it is delivered from the last reducing-pass 80 of the rolls in order to conduct it over the rod or bar which may at the time be passing through the curved repeaters C and D. In case the position of the reducing grooves or 85 passes 1, 2, and 3 were reversed and the larger groove were to be placed next the housing A, causing the motion of the rod as it is passed through the mill to be reversed from that I have above described, the inclined bottom of the groove F or run-out might be omitted, 90 provided the rod operated upon was short enough to cause its rear end to be carried through the rolls before its advancing end reached the next consecutive pass. In other words, if the length of the rod were less than 95 the circumference of the repeaters I place a plate or cover G over that section of the repeaters C and D next the rolls in order to prevent the buckling of the rod or bar in the repeaters, leaving the remaining portion of the 100

repeaters open to allow the rod or bar to be raised out of the repeaters in case the rod is delivered from one of the grooves or passes in the rolls faster than it is taken up by the next succeeding groove or pass, thereby producing a loop or "overfeed," as indicated by the broken lines H and I, and I provide means for relieving the overfeed by means of an inclined floor J, down which the overfeed is pushed aided by gravity due to the inclination of the floor. By giving a bend to the rod or bar immediately upon its delivery from the grooves or passes of the rolls I obviate the buckling of the bar between the rolls and the curved repeater and I also obviate the friction of the rod or bar against the remaining portion of the repeater.

So far as I am aware it is broadly new to accomplish the continuous reduction of a rod or bar by transferring the advancing end of the rod or bar around one of the roll-housings so the rod or bar delivered from a groove in the rolls will be entered into another groove in the same pair of rolls and its reduction continued, and I do not wish to confine myself to the specific means shown for transferring the end of the rod or bar around the roll-housings. The employment of repeaters C and D is a convenient method and one of many which may be employed for that purpose.

The gist of my invention consists in the idea of accomplishing the consecutive reduction of a rod or bar by the consecutive grooves or passes of a pair of rolls on what is known as a "two-high mill" by transferring the advancing end of the rod or bar around one of the housings of the rolls. The plate G covers substantially one half of each of the repeaters, leaving the other half open, which allows the loop or overfeed to be lifted out and to flow down the inclined floor J, as represented

by the broken lines H and I, the movement of the loops being in the direction of the arrow a, Fig. 1. If, however, the edge G of the covering-plate be arranged on the broken line K, Fig. 1, the direction of the overfeed or loops of the rod or bar would be changed and would proceed in the direction of the arrow b, and the loops would flow out in a line at an oblique angle to the axes of the rolls, as shown in Fig. 1. While the edge G' of the covering-plate G coincides substantially with the diameter of the repeaters, its position may be changed in order to change the movement of the overfeed, thereby directing the loops into a desired position on the floor of the mill.

What I claim as my invention, and desire to secure by Letters Patent, is—

1. The herein-described method of consecutively reducing a rod or bar in cross-section which consists in passing the rod or bar between two rolls and conducting or transferring the advancing end of the rod or bar around one of the housings of the rolls and thence between the rolls again and so on until suitably reduced in cross-section, substantially as described.

2. The within-described method of consecutively reducing a rod or bar in cross-section and consisting in passing the rod or bar through one of the grooves or passes in a pair of rolls, having a series of reducing grooves or passes, and conducting or transferring the advancing end of the rod or bar around one of the housings of the rolls to the next consecutive groove or pass and so on successively through the several grooves in the series.

Dated this 2d day of July, 1902.

JEROME R. GEORGE.
